UNITED STATES PATENT OFFICE.

JOHN N. TWEEDY, OF WEST FRANKFORT, ILLINOIS.

MINE-CAR COUPLER.

Application filed February 21, 1927. Serial No. 169,911.

This invention relates to coupling devices especially designed for use in connection with the draw bars of mine cars and aims to provide a coupler which may be detachably secured to a draw bar of a mine car to be engaged by a coupling link to couple cars.

An important object of the invention is to provide a device of this character which 10 will automatically operate when a coupling link is moved into the coupling head, eliminating the necessity of an operator moving a latch member or the like to couple cars.

A still further object of the invention is 15 to provide a coupler which will permit cars to round curves without danger of breaking or uncoupling the coupler.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:

Figure 1 is a central longitudinal sectional view through a coupling device constructed in accordance with the invention.

Figure 2 is a plan view thereof showing the same as connected with the draw bars of mine cars.

Figure 3 is a sectional view taken on line 35 3-3 of Figure 1.

Referring to the drawing in detail, the reference character 5 designates a portion of a mine car to which the tubular member 6 is secured, the tubular member acting as a support for the draw bar 7 which is formed with a head 8 at one end thereof.

A coiled spring indicated at 9 is housed by the tubular member 6 and has one of its 45 ends contacting with the head 8, the opposite end thereof contacting with the head 10 at the opposite end of the housing or tubular member 6 so that movement of the draw bar in one direction, will act to place the spring under tension and return the draw bar.

As clearly shown by the drawing, this head 10 is formed with an enlargement or irregular portion 11 cooperating with the collar 12 carried by the draw bar 7, and 55 which is constructed in a similar manner so

that rotary movement of the draw bar 7 is prevented, to the end that the draw bar 7 is held in a true horizontal position.

The coupler forming the essence of the present invention includes a hollow head 14 which has its ends flared as at 15 and 16 respectively so that movement of the draw bar and coupling 8, in horizontal planes, will be permitted without danger of directing lateral strain to the coupling head 14 to twist or render the same inoperative, when the mine cars equipped with the coupling are rounding a curve in the track.

The reference character 17 indicates a vertical bolt that passes through openings in 70 the coupler head 14, the bolt also passing through the usual pin opening of the draw bar, thereby connecting the coupler head and draw bar in a manner to permit of movement of the head with respect to the draw 75 bar.

Surrounding the bolt 17 is a coiled spring 18 that has one end thereof embedded in an opening in the coupler head, while the opposite end is positioned within an opening 80 of a draw bar 7, the tension of the spring being such as to normally move the coupling head to its normal position, thereby insuring the head being held in a position to receive the coupling link, associated therewith.

As shown by Figure 1, the head 14 is provided with an upstanding portion 19 which is provided with spaced ears formed with openings to receive the bolt 20 that provides 90 a pivot for the locking dog 21 that has a rearwardly extended tail piece 22 formed with an opening to receive the chain 23. This locking dog 21 is of a length to move within the cut out portion 24 which cut out 95 portion defines a shoulder 25 against which the locking dog is held in the coupling of cars.

In order that the locking dog may be moved to its inactive position, a pivoted dog 100 operating member 26 is provided, which has handle portions 27, to the end that as the arms 27 are moved, the locking dog may be elevated. When the locking dog is released, it will of course move to its normal 105 position by gravity.

The locking link is indicated by the reference character 28 and has a head 29 formed with a recess to receive the draw bar 30, the head being flared as shown by Figure 2 to 110

permit of swinging movement of the locking link.

The head of the locking link is connected with the draw bar 30 by means of the bolt 31 around which the coiled spring 32 is positioned, the spring having an upwardly extended end portion 33 fitted in an opening of the head, while the opposite end of the coiled spring fits in an opening of the drawing bar 30 to normally return the locking link to a position directly in front of the coupling head so that the link will automatically find its way into the coupling head when two cars are brought together.

From the foregoing it will be seen that a coupler constructed in accordance with the present invention may be readily and easily secured to the draw bars of mine cars and the mine cars coupled in such a way that they may move around curves or over short

switches without danger of the cars becoming uncoupled.

I claim:

A mine car coupling comprising a hollow coupler head having laterally flared front and rear portions and an upstanding portion having transverse aligning openings, a bolt extending through the openings, a locking dog pivotally mounted on the bolt, said head having a cut away portion defining a shoulder facing inwardly, said locking dog adapted to contact with the shoulder to restrict forward movement of the locking dog, and a coupling link adapted to engage the locking dog for locking cars equipped with the device, together. 25 30 35

In testimony that I claim the foregoing as my own, I have hereto affixed my signature.

JOHN N. TWEEDY.
